UNITED STATES PATENT OFFICE

2,088,194

RADIO RECEIVING SYSTEM

Paul O. Farnham, Mountain Lakes, N. J., assignor, by mesne assignments, to Radio Corporation of America, New York, N. Y., a corporation of Delaware

Application April 11, 1934, Serial No. 720,113
Renewed June 6, 1936

12 Claims. (Cl. 250—20)

This invention relates to radio receiving systems and particularly to radio receivers of the automatic gain control type.

This application is a continuation-in-part of my copending application Ser. No. 641,280, filed Nov. 4, 1932, Patent No. 2,003,100, May 28, 1935.

Various circuit arrangements have been proposed for automatically regulating the sensitivity of a radio receiver to maintain a radio voltage level at the detector which is approximately constant over a wide range in the magnitude of the radio voltage at the receiver input terminals. The advantage of such receivers is that the operator need make little or no adjustments to obtain a constant audio output level when tuning to signals of different intensity or when tuned to a signal which tends to vary in intensity. The general method previously employed to apply an "automatic gain control" to the radio amplifier portion of a receiver has been to rectify the carrier component of an amplified radio voltage to produce a direct current voltage that varied as a substantially linear function of the radio input to the detector, and to impress such direct current voltage upon the radio amplifier as a gain control voltage. The application of the prior types of automatic gain control systems to radio amplifiers of high selectivity has resulted in an apparent, or a real, loss in selectivity as the audio output did not fall off until the receiver was detuned far from resonance at the frequency of a nearby broadcasting station. Unfortunately, however, the quality of reproduction fell off rapidly with detuning, although the output level remained constant, and tuning or resonance meters were required in addition to the usual tuning scale.

The known types of automatic gain control receivers are well exemplified by the patent to Graham, No. 1,851,387, which illustrates the automatic gain control system employed in the Model No. 846 radio receiver manufactured commercially by the Stromberg-Carlson Telephone Manufacturing Company. This particular receiver included a tuning meter and, as stated in the "Engineering Data Book for Stromberg-Carlson No. 846 Radio Receiver", page 9:

"The meter must be used for this indication as, in the case of powerful signals, the volume does not change for a certain distance each side of the resonance point."

The prior types of automatic gain control receivers have therefore been relatively expensive due to the necessity of including a tuning meter in the receiver, and the operation of such receivers has been complicated by the fact that the operator must tune the receiver from the indications of both a tuning scale and a tuning meter.

60 An object of the present invention is to pro-

vide a radio receiver of the automatic gain control type which is free from the objections of the prior receivers of this type. An object is to provide a radio receiver of the automatic gain control type which is characterized by high selectivity. A further object is to provide methods of and apparatus for automatic gain control in radio receivers which are characterized by a greater selectivity in the transmission of amplified radio-frequency voltages impressed on the detector element of the receiver than in the transmission of the amplified radio voltage to the rectifier of the automatic gain control system.

These and other objects of the invention will be apparent from the following specification when taken with the accompanying drawing in which:

Fig. 1 is a fragmentary circuit diagram of a superheterodyne radio receiver embodying the invention; and

Fig. 2 is a fragmentary circuit diagram of a 20 tuned radio frequency amplifier embodying the invention.

In the drawing, the reference character 1 identifies a radio frequency amplifier, including one or more vacuum tubes, a local oscillator and a frequency changer, which receives carrier wave energy from an appropriate collector structure and which works into a detector and audio amplifier or other load circuit. The exact design and construction of the superheterodyne system is not an essential part of the present invention, and only the last tube 2 of the intermediate frequency amplifier is illustrated.

The tuned output circuit 3 of the last amplifier stage is coupled, with critical or slightly greater than critical coupling, to the tuned input circuit 4 of the detector and automatic control stage of the receiver, the radio voltage E_0 which is built up across the primary circuit 3 establishing a radio voltage E across the secondary circuit 4. The single tube 5 of the combination detector-control stage may be a tube known as "type 55" and includes a pair of rectifying anodes A_1 , A_2 , a control grid G , plate P and a cathode K .

Referring first to the circuit elements which cooperate with the tube 5 to give the stage the function of a detector and an audio frequency amplifier, the high potential terminal of the tuned input circuit 4 is directly connected to the anode A_2 , and the opposite terminal is connected to the cathode K through an audio frequency resistance 6 and an audio frequency by-pass condenser 7, the resistance 6 being by-passed for radio frequency by a condenser 8. The audio frequency voltage developed by diode rectification across the resistance 6 is impressed upon the control grid G through a filter comprising resistance 9 and a radio frequency condenser 10. The plate circuit includes the primary winding 25

of an audio frequency transformer 11, preferably provided with means such as a shunt resistance 12 and adjustable tap 13 for controlling the output level of the receiver system, and a source of 5 direct current potential +B which is connected to ground or -B through the voltage divider formed by resistances 14, 15. The cathode K is connected to ground through a resistor 16 which is by-passed for audio frequency by the condenser 17. A direct current path for impressing a bias voltage between the anode A₂ and the cathode K is completed by the resistance 18 which is connected between the resistance 6 and the junction of the resistances 14, 15, of the voltage divider. 10 The flow of plate current through the cathode resistor 16 will establish a potential drop E₁ which places the cathode K at a more positive direct current potential than that of ground or -B. The direct current voltage E₂ across the voltage 15 divider 14, 15 gives rise to a potential E₃ across resistance 14 which applies a positive potential to the anode A₂.

The bias voltage on the anode A₂ is equal to the difference of the voltages E₁ and E₃. The voltage 25 E₃ and the value of resistance 16 are so chosen that, when the input voltage E is zero, a sufficient plate current will flow in the tube 5 to make the voltage E₁ greater than the fixed voltage E₃. In other words, the plate current has a normal value 30 in the absence of received signals which is sufficient to maintain the anode A₂ and the control grid G at direct current potentials which are negative with respect to the cathode. It therefore follows that small peak values of E less than 35 E₁-E₃ will not be rectified in the anode A₂-cathode circuit and hence no audio frequency voltage will be developed across the resistor 6.

Attention is directed to the fact that the connection between the audio frequency resistance 6 40 and the grid G will impress both the rectified audio voltage and the rectified direct current voltage upon the grid G, thus causing the tube 5 to function as an amplifier for any direct current voltage developed across resistance 6. This amplified direct current voltage operates to reduce or remove the bias voltages normally impressed upon the anode A₂ and the grid G. When the peak value of the radio input voltage E exceeds the bias voltage E₁-E₃ on the anode A₂, rectification 45 takes place in the circuit including the elements A₂, G and an additional negative bias is thus impressed upon the control grid, which bias effects a reduction in the plate current flow. The consequent reduction in the voltage E₁ across resistance 16 removes the initial bias E₁-E₃ on the anode A₂, and the normal diode detection then 50 takes place in that circuit. The direct current voltage developed across resistance 6 by rectification, together with the decrease in the voltage E₁ across the cathode resistance 16 serves to maintain the control grid bias at a value suitable for 55 audio frequency amplification.

A bias voltage for automatically controlling the gain of amplifier 1 is developed between anode 60 A₁ and cathode K by connecting anode A₁ to the tuned primary circuit 3 through a radio frequency condenser 19 and to ground through a resistance 20. The anode terminal of resistance 20 is connected through a filter comprising resistance 21 65 and condenser 22 to the lead 23 which extends to the control grid circuits of the tube or tubes of amplifier 1.

It is desirable that the magnitudes of the radio voltages, E and E₀, be so related that when the 70 detector input E is increased to that value suffi-

cient to make the voltage drop E₁ across the cathode resistance 16 equal to the fixed bias component E₃, the peak voltage E₀ on the automatic gain control anode will be equal to E₁, and thus initiate the action of the automatic gain control. 75 To make the voltage E₀ greater than E, the inductance of the primary tuned circuit 3 may be larger than that of the secondary circuit 4.

The operation of the circuit is as follows. So long as the peak detector input voltage E is less than the negative bias voltage, E₁-E₃, on the anode A₂, there will be no rectification of the impressed voltage E by the diode A₂-K. Nor will there be any incidental rectification of radio voltages in the triode amplifier circuit since the filter, resistance 9 and condenser 10, prevents radio voltages from reaching grid G.

The voltage E₁ due to plate current flow with no input to the amplifier elements is relatively high and transmission of any audio frequency 20 signals by the amplifier is effectively suppressed. When the peak voltage E exceeds the negative bias on anode A₂, rectification takes place and the direct current and audio frequency voltages developed across resistance 6 are impressed on the 25 grid G. The rectified direct current voltage increases the negative bias on grid G, thus reducing the plate current and thereby reducing the voltage E₁. This reduces the delay action bias voltage 30 on anode A₂, and reduces the negative bias on grid G to a value appropriate for audio amplification.

Turning now to the automatic gain control, the delay action bias voltage on anode A₁ is equal to E₁. As soon as rectification takes place in the 35 detector diode circuit, the voltage E₁ is reduced by the direct current amplifier action of the triode elements and the delay bias is thus removed from the automatic gain control diode. The rate at which a gain control voltage is developed, with 40 increasing radio input voltage E₀, is therefore more rapid than is the case when a fixed delay bias voltage is impressed upon the gain control rectifier. This method of and circuit arrangements for removing the delay bias impressed on a 45 gain control rectifier are described and claimed in my copending application Ser. No. 641,279, filed Nov. 4, 1932.

The important feature of the described circuit is the feeding of the rectifier A₁-K from the primary tuned circuit 3 and the feeding of the detector A₂-K from the secondary tuned circuit 4. As is customary in the design and construction of intermediate frequency transformers, the tuned 50 circuits are coupled with critical or slightly greater than critical coupling to obtain high selectivity in the intermediate frequency amplifier. The significance of this circuit arrangement and this degree of coupling is that the selectivity of transmission to the detector is greater than the selectivity of transmission to the rectifier of the gain control system. It is also advantageous for the purpose of obtaining differential selectivity effects to have the power ratio

$$\frac{R}{\omega L}$$

of the secondary circuit less than that of the primary circuit.

The effective result of this differential selectivity is that the radio input to the rectifier does not fall off as rapidly with detuning from exact resonance at a transmission channel as does the input to the detector. The audio output therefore falls off rapidly with detuning since the gain 75

is not increased as an inverse function of the input to the detector, but as an inverse function of the input to the rectifier. The differential selectivity therefore prevents the amplifier gain from rising at such a rate as to destroy the selectivity of the receiver.

Substantially the same arrangement may be used in receivers of the tuned radio frequency type in which the detector works out of a pair of tuned circuits coupled with critical or somewhat greater than critical coupling. The invention may be applied to the customary type of cascaded radio amplifier employing only one tuned circuit in each interstage coupling, as shown in Fig. 2. A two-stage radio amplifier employing screen grid tubes 24 is illustrated but it is to be understood that the exact number of cascaded stages is not material. The tuned input circuit of the first amplifier tube is connected in any appropriate manner with the antenna A and similar tuned input circuits 26 are provided for the subsequent radio amplifier tube or tubes 24 and for the detector tube 27, the tuning condensers of all of the circuits being preferably mechanically connected, as indicated by the broken line 28, for simultaneous adjustment. The inductances of the tuned circuits 26 are closely coupled to the plate inductances 29 of the screen grid amplifier tubes 24 of the preceding stage, as is customary in the design of coupling circuits for use with screen grid amplifiers. An appropriate method for obtaining the close coupling between the un-tuned primary and the tuned secondary is to wind the secondary as a close solenoidal winding on a cylindrical form and to wind the primary winding directly over the secondary coil. This will provide the tight coupling which is necessary to obtain adequate gain in a tuned radio amplifier of the illustrated type.

The grid of the rectifier tube 30 of the automatic gain control system is connected to the high potential terminal of the input circuit 26 of the last radio amplifier tube 24 through a coupling condenser 31 and the control grid of the first radio amplifier tube 24 is connected to the plate of the tube 30, while the control grid of the second amplifier tube 24 is connected to an intermediate point in the resistance 32 which is connected between the plate of tube 30 and the ground or neutral point of the receiver. The control grids of the amplifier tubes 24 are separated from their respective input circuits by blocking condensers 33 and the low potential terminals of their input circuits are directly connected to the ground or neutral point. An intermediate point of the voltage divider 35 of an appropriate power supply system is connected to the ground or neutral point to determine the direct current potential of that point; the cathode of the control tube being connected to a point on the voltage divider 35 which is negative with respect to the direct current voltage of the plate connection. The control grid of the tube 30 is connected through a grid resistance 36 to a point of more negative potential on the voltage divider 35 to provide a grid bias for the control tube which is appropriate for rectification. A condenser 37 is shunted across the plate resistance 32 of the control tube to prevent the development of radio and audio voltages in the output circuit of the control tube.

It will be apparent that the selectivity of transmission of amplified radio voltages to the detector is greater than the selectivity of transmission to the control tube. The receiver will therefore

have a high selectivity since the automatic gain control bias impressed on the amplifier tubes 24 is determined by the amplified radio voltage impressed on the control tube and not by the radio input to the detector. The signal voltage at the detector falls off rapidly as the amplifier is detuned from resonance at a signal frequency but the gain is not automatically increased at an inverse rate.

The foregoing examples of receiver designs for obtaining a higher selectivity at the detector than at the rectifier of the automatic gain control system are merely illustrative of the invention, and the preferred or appropriate circuit arrangement for obtaining differential selectivity with other types of amplifiers will be apparent to those skilled in the design and construction of radio receivers and amplifiers.

I claim:

1. In a radio receiver, the combination with a tuned radio amplifier working into a gain control rectifier system and into a detector, and means energized by said rectifier system for automatically controlling the gain of said amplifier, of means for imparting greater selectivity to the radio voltage impressed by said amplifier upon said detector than to the radio voltage impressed by said amplifier upon said rectifier, said second means including at least two coupled circuits connected in cascade between said amplifier and detector, the radio voltage for said rectifier being derived from the first of said cascaded circuits, and the power ratio of said first circuit being greater than that of the second cascaded circuit.

2. A radio receiver of the type including a tuned radio amplifier, a gain control rectifier and a detector, and a pair of coupled tuned circuits arranged in cascade coupling said amplifier to said rectifier and detector to impress thereon radio voltages which vary with the amplified radio output of said amplifier, the second tuned circuit being connected to the detector, the first of said tuned radio circuits being connected to said rectifier for obtaining greater selectivity in the radio input to said detector than in the radio input to said rectifier, and the power ratio of the second of the tuned circuits being less than the power ratio of the first of the tuned circuits.

3. In a radio receiver, a tuned radio amplifier, a detector, coupling means between said amplifier and detector including a tuned output circuit for said amplifier having approximately critical coupling with a tuned input circuit of the detector, and means for automatically controlling the gain of said amplifier as a function of the radio input to the receiver, said automatic gain control means including a rectifier having an input circuit connected across the tuned output circuit of said amplifier, and the amplifier tuner output circuit power ratio exceeding that of the detector tuned input circuit.

4. In a radio receiver provided with a signal amplifier having a tuned output circuit, a diode detector network having a tuned input circuit, said output and input circuits being reactively coupled, the constants of the coupled circuits being proportioned to impart a power ratio to the diode input circuit which is less than that of the amplifier output circuit, a diode rectifier network having its diode electrodes connected across the amplifier output circuit, said rectifier network including a direct current connection to the amplifier input circuit for regulating the gain of the amplifier in response to signal amplitude variations, and both said diodes including a com-

mon cathode and having their electrodes in a common tube envelope.

5. In a radio signaling system provided with a signal transmission tube having a tuned output circuit, a signal utilization network including an electron discharge tube having a tuned input circuit, said output and input circuits being coupled, the constants of said output circuit and input circuit being proportioned to impart a power ratio to the said input circuit which is less than that of said transmission tube output circuit, means for deriving from signals transmitted through said system a unidirectional voltage which is dependent upon the transmitted signal amplitude, said last means being connected to said transmission tube output circuit in order to derive signal energy therefrom, said last means including a direct current connection to a gain control electrode of said signal transmission tube for regulating the gain of said tube in response to signal amplitude variations.

6. In a radio receiver of the type provided with a signal amplifier whose gain is to be automatically regulated in dependence upon variations in received signal amplitude, a multiple function tube comprising a cathode, a signal input grid, and at least an output plate, an audio frequency load circuit coupled to the plate, at least two anodes disposed within said tube, a transformer having a tuned primary circuit and a tuned secondary circuit connected to the output electrodes of said amplifier, said transformer circuits being tuned to a desired signal frequency, said tuned secondary circuit being coupled to the cathode and one of said anodes and including a load impedance for developing an audio frequency voltage from detected signal currents, means for impressing the audio frequency voltage upon said input grid of said tube, means connecting the cathode and second anode of said tube across said primary tuned circuit, and means electrically connected with said primary tuned circuit for developing a direct current voltage from said signal currents which varies in magnitude with the received signal amplitude, and additional means for impressing said direct current voltage upon said amplifier as a gain control voltage.

7. In a radio receiver of the type provided with a signal amplifier whose gain is to be automatically regulated in dependence upon variations in received signal amplitude, a multiple function tube comprising a cathode, a signal input grid, and at least an output plate, an audio frequency load circuit coupled to the plate, at least two anodes disposed within said tube, a transformer having a tuned primary circuit and a tuned secondary circuit connected to the output electrodes of said amplifier, said transformer circuits being tuned to a desired signal frequency, said tuned secondary circuit being coupled to the cathode and one of said anodes and including a load impedance for developing an audio frequency voltage from detected signal currents, means for impressing the audio frequency voltage upon said input grid of said tube, means connecting the cathode and second anode of said tube across said primary tuned circuit, and means electrically connected with said primary tuned circuit for developing a direct current voltage from said signal currents which varies in magnitude with the received signal amplitude, additional means for impressing said direct current voltage upon said amplifier as a gain control voltage, and said anodes being disposed outside

the electron stream flowing from said cathode to said plate.

8. In a radio receiver of the type provided with a signal amplifier whose gain is to be automatically regulated in dependence upon variations in received signal amplitude, a multiple function tube comprising a cathode, a signal input grid, and at least an output plate, an audio frequency load circuit coupled to the plate, at least two anodes disposed within said tube, a transformer having a tuned primary circuit and a tuned secondary circuit connected to the output electrodes of said amplifier, said transformer circuits being tuned to a desired signal frequency, said tuned secondary circuit being coupled to the cathode and one of said anodes and including a load impedance for developing an audio frequency voltage from detected signal currents, means for impressing the audio frequency voltage upon said input grid of said tube, means connecting the cathode and second anode of said tube across said primary tuned circuit, and means electrically connected with said primary tuned circuit for developing a direct current voltage from said signal currents which varies in magnitude with the received signal amplitude, additional means for impressing said direct current voltage upon said amplifier as a gain control voltage, and a resistor disposed in the space current path flowing from said plate to said cathode for developing a direct current voltage, and means for impressing said last named voltage upon said input grid to provide a normal operating bias therefor.

9. In combination with a tube of the type including an amplifier section and a pair of independent diode sections, all of said sections having a common cathode, a source of signal waves, a transformer having resonant primary and secondary circuits both tuned to a common wave frequency, means coupling one of the diode sections across said primary tuned circuit, and providing a wave rectifier circuit which develops a direct current voltage, means coupling the other diode section across the secondary tuned circuit and providing a wave rectifier circuit developing an audio frequency voltage, and means impressing the audio voltage upon the input electrode of said amplifier section.

10. In combination with a tube of the type including an amplifier section and a pair of independent diode sections, all of said sections having a common cathode, a source of signal waves, a transformer having resonant primary and secondary circuits both tuned to a common wave frequency, means coupling one of the diode sections across said primary tuned circuit, and providing a wave rectifier circuit which develops a direct current voltage, means coupling the other diode section across the secondary tuned circuit and providing a wave rectifier circuit developing an audio frequency voltage, means impressing the audio voltage upon the input electrode of said amplifier section, and an audio frequency load circuit connected to the output electrode of the amplifier section.

11. In combination with a tube of the type including an amplifier section and a pair of independent diode sections, all of said sections having a common cathode, a source of signal waves, a transformer having resonant primary and secondary circuits both tuned to a common wave frequency, means coupling one of the diode sections across said primary tuned circuit, and providing a wave rectifier circuit which develops a direct current voltage, means coupling the other

diode section across the secondary tuned circuit and providing a wave rectifier circuit developing an audio frequency voltage, means impressing the audio voltage upon the input electrode of said amplifier section, an audio frequency load circuit connected to the output electrode of the amplifier section, said wave source including a transmission tube, and a direct current connection between a gain control electrode of said 10 transmission tube and said primary rectifier circuit.

12. In combination with a tube of the type including an amplifier section and a pair of independent diode sections, all of said sections having 15 a common cathode, a source of signal waves, a

transformer having resonant primary and secondary circuits both tuned to a common wave frequency, means coupling one of the diode sections across said primary tuned circuit, and providing a wave rectifier circuit which develops a 5 direct current voltage, means coupling the other diode section across the secondary tuned circuit and providing a wave rectifier circuit developing an audio frequency voltage, means impressing the audio voltage upon the input electrode of said 10 amplifier section, and means in the space current path of said amplifier section for developing a delay bias for the anode of said first diode section.

PAUL O. FARNHAM.
